CLAIM

The ornamental design for a socket organizer with a handle, as shown and described.

DESCRIPTION

FIG. 1 is a perspective view of a socket organizer with a handle showing my new design;

FIG. 2 is a front elevational view thereof;

FIG. 3 is a left side elevational view, the right side being a mirror image thereof;

FIG. 4 is a top plan view thereof, with the lid open;

FIG. 5 is a top plan view thereof, with the lid closed;

FIG. 6 is a bottom plan view thereof.
